CLOTH MARKING APPARATUS

Lyman Hamrick, Gaffney, S. C.

Application June 12, 1939, Serial No. 278,736

7 Claims. (Cl. 101—216)

This invention relates to a machine for marking successive outlines of a design on a flexible sheet of material, such as cloth, paper and the like. In the production of bedspreads or other like materials, it is necessary to first mark a plain sheet of material with an outline so that in subsequent operations, an ornamental design can be placed on the marked outline. After the design has been placed on the outline by any suitable means such as a tufting machine, the article is washed thereby removing the marks.

It is, therefore, an object of this invention to provide a machine which is capable of reproducing in rapid succession, the outline of a pattern upon a sheet of material. One form of the invention comprises a pattern roll and an adjacent marking roll, between which the material to be outlined is passed. At the point where the marking roll contacts the cloth, the direction of travel of the cloth is in an opposite direction, to the direction of travel of the marking roll, thereby producing a rubbing action at this point to insure that the material will be properly marked.

It is another object of this invention to produce a marking machine comprising a pattern roll and an adjacent constantly driven marking roll between which a fabric or other material is adapted to be drawn, with means for yieldingly holding the roll and the fabric in contact with the pattern.

Also means are provided for reciprocating the marking roll axially during the marking operation so that an even wear of the marking material will occur.

It is a further object of this invention to provide an apparatus of the class described having an appliance for lifting the material to be marked and the marking roll out of engagement with the pattern and the pattern roll. In the manufacture of bedspreads, it is undesirable to have a seam intermediate the ends of the spread. Therefore, when a seam occurs in the material to be marked, it is necessary to stop the machine and then reposition the pattern and the pattern roll so that a design will begin at the seam. To reposition the pattern roll, the pressure exerted thereon by the marking roll and material to be marked must be relieved.

It is a further object of this invention to provide a marking apparatus comprising a fixed marking roll and a fixed pattern roll having a pattern therearound, between which a sheet of material to be marked is passed, the pattern roll being covered with a resilient material of padding, such as sponge rubber to act as a base for the pattern. This padding will enable the pattern to give way to any irregularity in the marking roll and insure relatively uniform pressure. In this form of the invention an axial reciprocation is also provided for the marking roll.

It is a still further object of this invention to provide a marking apparatus comprising a pattern roll having a pattern therearound, over which flexible material passes to be marked, and a dye applicator roll normally contacting said pattern before it moves beneath the material. By thus positioning the various parts, the dye will be transferred from the applicator roll to the pattern, and thence from the pattern to the material to be marked. It is usually desirable to use a fugitive dye in this form of the invention so that when the finished fabric is washed the outline will disappear.

Some of the objects of the invention having been stated, other objects will appear as the description proceeds when taken in connection with the accompanying drawings, in which—

Figure 1 is a plan view of my marking apparatus;

Figure 2 is a side elevation of the apparatus shown in Figure 1;

Figure 3 is a vertical longitudinal sectional view taken along the line 3—3 in Figure 1;

Figure 4 is an exploded isometric detail view showing portions of the pattern roll, the pattern, and the fastening bar for securing these members in position;

Figure 5 is an elevation showing a slightly modified form of the invention in which both the pattern roll and the marking roll are fixed, and a sponge rubber base is employed for supporting the pattern;

Figure 6 is a sectional plan view taken along the line 6—6 in Figure 5;

Figure 7 is a longitudinal vertical sectional view showing another modified form of the invention in which a fugitive dye solution is employed for marking the material;

Figure 8 is a plan view, with the central portion thereof broken away showing a suitable pattern which is adapted to be placed upon the pattern rolls.

Referring more specifically to the drawings, the numerals 10 and 11 denote the side frames for my improved cloth marking machine which have mounted thereon bearings 12 and 14 in which is journaled a shaft 15. The intermediate portion of shaft 15 supports a pattern cylinder 16, said pattern cylinder having a longitudinal groove 17 therein, for the reception of the ends of a suitable pattern 18. Figures 2 and 3 show the pattern 18 fixed in the groove 17; whereas Figure 4 shows the pattern removed.

By referring to Figures 4 and 8 it is seen that the pattern 18 has a plurality of raised designs 19 on the top side thereof, and at each end a slide fastener 20 is provided. When the pattern is placed around the cylinder 16 the two slide fasteners 20 are interlocked with each other by a suitable slide locking member 22 in

the manner shown in Figure 4. After locking the ends of the pattern, the interlocked portion is inserted within the groove 17 and then a bar 23 is inserted on top of the interlocked portion 5 to firmly hold the pattern in position on the cylinder 16. When the pattern is installed on the cylinder the raised projections 19 are disposed on the outer periphery.

A suitable lap pin 26 has a roll of material 27 10 such as cloth or the like wound therearound. The ends of the lap pin are mounted in suitable forked bearings 28 and 29, said bearings having their lower ends rotatably mounted in cantilevered supports 30 and 31, respectively. These 15 supports are carried by vertically disposed shafts 32 and 33 which are rotatably mounted in bearings 34 and 35, secured to side supports 10 and 11, respectively.

The vertically disposed shaft 33 has a laterally 20 extending arm 37 to which is pivotally secured one end of a rod 38, the other end of said rod being pivotally secured to the lower end of a hand lever 39. The intermediate portion of lever 39 is pivoted as at 40 to a rack 41, said 25 rack being engaged by projecting dog 42 which is normally pressed into engagement with the teeth in this rack by means of a suitable compression spring 43. A vertically disposed link 44 and pivoted lever 45 are employed for raising 30 the dog 42 out of engagement with the rack when it is desired to rotate the lever 39 about its pivot point 40. It is seen by observing Figures 1 and 2 that when the lever 39 is rotated, that the cantilevered supports 30 and 31 35 together with the beam 27 will be shifted laterally of the machine. This is necessary to align the sheet material with the drum 16.

A layer of sheet material 48 is drawn from the beam 27 upwardly over a spreader roll 49 and 40 then downwardly beneath another roller 50. After leaving the roller 50 the material 48 contacts the outer periphery of the pattern 18 on cylinder 16 for a substantial distance. The rollers 49 and 50 are mounted between side frames 10 45 and 11.

The spreader roller 49 has left-hand threads 49a on the far end and right-hand threads 49b on the near side (Figure 1). The normal direction of rotation of the roller 49 is clockwise in 50 Figure 2, therefore, at the point the material 48 contacts the roller 49, the direction of travel of the roller will be opposite to that of the direction of travel of the cloth. These opposed directions will produce a spreading action to keep all 55 portions of the sheet material taut. In order to produce this counter rotation of the spreader roll 49, a suitable pulley 55 is provided on one end thereof upon which a belt 56 is mounted. This belt is also mounted upon a pulley 57, which 60 is secured to the end of a shaft 58. The shaft 58 is rotatably mounted in the side frames 10 and 11 and has a roller 59 mounted on the intermediate portions thereof (see Figure 3) beneath which the cloth or other material 48 passes 65 after leaving the pattern 18 on the cylinder 16. This roller 49 is positively driven by a suitable gear 60 on the end of shaft 58 (see Figure 2), which gear meshes with a pinion 61 on a shaft 62, said shaft 62 being rotatably mounted between supporting sidewalls 10 and 11. Shaft 62 70 also has a pulley 64 fixedly secured thereon upon which a belt 65 is mounted. This belt is connected to a suitable source of power, not shown, for operating the cloth marking machine. It 75 can be seen that since the shaft 58 rotates in a

clockwise manner in Figures 2 and 3, that a similar direction of rotation will be imparted to the pulleys 55 and 57, and the spreader roller 49 to cause the sheet material to be spread laterally of its line of travel.

The gear 60 (Figure 2) also meshes with an idler intermediate pinion 66, and this pinion, in turn, meshes with a gear 67 on the end of a transversely disposed shaft 68. The shaft 68 is rotatably mounted in the side frames 10 and 11 and has fixedly secured on the intermediate portion thereof, a roller 69. The rollers 59 and 69 (see Figure 3) support a take-up roll of material 70 which is formed from the layer of material 48 after it passes over the pattern cylinder. Both the rollers 59 and 69 rotate in a clockwise direction, but due to the fact that the gear 67 (Figure 2) has a few less teeth therein than the gear 60 the rate of rotation of the roller 69 is slightly greater than the rate of rotation 20 of the roller 59; consequently, there will be a tendency while the take-up roll 70 is being formed for this roll to gradually become more compact.

Between the rollers 59 and 69, the sheet material 48 is adapted to contact the pattern 18 25 on the cylinder 16. At a point where the material contacts the pattern, it is desirable to place a suitable marking roller, such as indicated by reference character 75, which is mounted around transversely disposed shaft 76. This 30 shaft is rotatably mounted in bearings 77 and 78 which are slidably mounted in slides 79 and 80 on sidewall members 10 and 11, respectively. Secured to each of the bearings 77 and 78 is a cord 82, said cord being adapted to pass over a 35 roller 83 and thence downwardly. On the lower end of each cord is a suitable weight 84 which normally maintains tension in the cord 82 and serves to hold the marking roller 75 against the portion of cloth 48 which is disposed around the 40 pattern cylinder. In other words, the weights 84 resiliently and yieldingly hold the marking roller 75 in contact with the cloth and the pattern on the pattern cylinder.

The shaft 76, which supports the marking 45 roller 75, has a sprocket 86 fixedly secured on one end thereof (see Figures 1 and 2). Upon this sprocket is mounted a chain 87 which is also mounted upon a second sprocket 88 on shaft 62. The intermediate portion of chain 87 is contacted 50 by a suitable tightener pulley 89, said pulley being pivoted as at 90 on the side frame 11. As the shaft 62 and pulley 64 rotate in a counter-clockwise manner in Figure 2, a similar rotation will be imparted to the marking roll 75, at the 55 point of contact with the pattern cylinder and the material to be marked, is in an opposite direction to the direction of travel of the material 48, and the pattern cylinder; consequently, a rubbing action will be effected.

In order to insure that all portions of the periphery of marking roll 75 will wear uniformly, a suitable means for axially reciprocating marking roller 75 and its shaft has been provided. This reciprocating means comprises a suitable cam 92 65 having a meandering serpentine groove 93 therein which is fixedly secured around the shaft 76. A stationary pin 94 is adapted to fit in groove 93 and this pin is supported by the bracket 78. It is seen that as the marking roll 75 rotates 70 that the pin 94 which remains in a fixed position will cause the cam to reciprocate toward and away from the observer a slight amount thereby causing the marking roller to move axially as it rotates and more evenly distribute the wear on 75

the marking material. The marking material may be composed of any suitable material such as a chalk-like formation, or it may be composed of an oleaginous material such as paraffin 5 mixed with coloring pigment.

When cloth is being marked by this machine, it is necessary to combine a plurality of lengths into a roll such as shown by reference character 27. These lengths are sufficient to form a plurality of bedspreads and are united into one continuous sheet by means of a seam. It is very undesirable that a bedspread be formed with a seam intermediate its ends, therefore, when the marking apparatus approaches a seam, it is either necessary to discard the marked bedspread which includes the seam or it is necessary to stop the machine and reposition the pattern cylinder so that the pattern will begin at the seam. The latter method will eliminate waste of at least a portion of a bedspread.

When it is desired to reposition the pattern and the pattern cylinder, it is necessary to release the frictional contact of the marking roller 75 and the sheet, material 48. In order to do this, a pair of spider members 100 and 101 have been rotatably mounted around shaft 15. These spider members have arc rims 102 and 103 respectively integral therewith, said arc portions being on a slightly greater radius from the axis 15 than the periphery of the pattern cylinder. Between the arc members 102 and 103, suitable transversely disposed rods 104 are secured which are adapted to move in close proximity to the periphery of the pattern 18 on the pattern cylinder 16. When in normal position the spider members are as shown in Figure 2; whereas when in an operative position, so that the cloth or sheet material 48 will be raised from the periphery of the pattern cylinder, the spiders are in the position shown in Figure 3. The arc member 102 and 40 103 have secured thereto as at 106 and 107, suitable cords 108 and 109. The other ends of these cords extend upwardly and are secured to pulleys 110 and 111, respectively, said pulleys, in turn, being secured to a transversely disposed shaft 45 112. The ends of the shaft 112 are rotatably mounted in bearings 114 and 115. The bearing 115 (Figure 2) has a pivoted dog 116, the free end of which is adapted to engage ratchet 117, which 50 ratchet forms an integral part of pulley 111. Upon one end of the shaft 112 a crank 118 is placed, which is used for winding the cords 108 and 109 around the pulleys 110 and 111 to thereby cause the spider members 100 and 101 to move from the position shown in Figure 2 to the position 55 shown in Figure 3, at which time the material 48 will be removed from binding contact with the periphery of the pattern roll 16.

It will also be noted that the arc members 102 and 103 have integral with their forward ends, suitable cam projections 102a and 103a. These projections extend inwardly towards the center of the pattern cylinder and serve to engage the extremities of the marking roller 75 and to remove this roller away from the pattern roller at the same time the sheet material 48 is being removed therefrom. The ratchet 117 and pawl 116 serve to hold the spider members in raised position, but when it is desired to return the members 70 to lowermost normal position the ratchet 116 is released thereby allowing the shaft 112 to rotate in a clockwise manner and release the spider members. When the spider members are in raised uppermost position, as shown in Figure 3, the cylinder 16 may be repositioned by a partial ro-

5 tation so that the junction point of the pattern 18 as designated by the slide fasteners 20 and 22 and slot 17 will coincide with the seam. This repositioning is effected by means of a suitable hand wheel 120 which is fixedly secured on the end of pattern cylinder shaft 16.

Figures 5 and 6 show a slightly modified form of the invention in which like reference characters will apply to like parts and a description will be made only of the parts and arrangements 10 which differ from those of the preceding form. In this form, the side frames 10 and 11 have suitable slides 130 and 131 mounted thereon, in which is adjustably mounted bearings 132 and 133, respectively. Journalized in these bearings are the ends of shaft 76 which carries the marking material 75. The bearing 132 has a cap plate 134 secured to one side thereof (see Figure 6), which plate rotatably confines the righthand end of a threaded rod 135 against the bearing. This 20 rod has its intermediate portion threadably secured in upstanding projection 136 of the slide 130 and a suitable hand wheel 137 is provided on the extreme left-hand end thereof for turning the rod 135 and thereby adjusting the position of 25 bearing 132 and its associated parts relative to the stationary slide 130. Likewise the slide 131 has a similar upstanding projection 138, and this projection has threadably mounted therein the intermediate portion of rod 139, said rod having a 30 hand wheel 140 on its left hand end and having its right hand end rotatably secured to one side of the bearing 133 by means of a plate 141. This plate 141 extends inwardly toward the marking roll and has a pin 142 extending laterally therefrom which penetrates a suitable serpentine groove 143 in a cam 144 which cam is fixedly secured around the shaft 76. As the marking roller 75 rotates the stationary pin 142 will cause the cam 144 and its associated roller 75 and shaft 40 76 to move axially back and forth, and produce an even wear on the periphery of the marking roller as it engages the sheet material 48 and the pattern on the cylinder 16. It is therefore seen that the marking roll remains in a stationary position so far as movement toward and away from the pattern cylinder is concerned.

The pattern cylinder 16 differs from that of the preceding form in that its periphery has a resilient padding such as sponge rubber 148 secured thereto and over this sponge rubber the pattern 18 is adapted to fit. The sponge rubber affords the necessary resiliency between the two cylinders to account for any irregularities in either member. When the marking roller 75 has 55 worn a substantial amount, it is only necessary to adjust the rods 135 and 139 to move the marking roll into closer engagement with the pattern on the pattern cylinder.

Figure 7 shows another modified form of the 60 invention in which a liquid dye is applied to the pattern 18 directly and the pattern, in turn, applies the dye solution to the material 48. In this form of the invention, the pattern cylinder 16 is rotatably mounted between two side frame 65 members 150 as well as members 49, 50, 59, 62 and 69. Disposed beneath the pattern cylinder 16 is a rubber covered applicator roller 151, the ends of which are rotatably mounted in suitable bars such as 152. These bars are penetrated by 70 upstanding dowel pins 153 which are anchored in a trough 154. In order to resiliently hold the roller 151 in contact with the cylinder 16, suitable compression springs 155 are mounted around dowel pins 153, between the upper side of the 75

trough 154 and the lower side of the bar 152. Disposed in this trough is a solution such as a fugitive dye 156 and this dye solution has the lower portion of the applicator roll 151 submerged therein. As the pattern cylinder 16 is rotated in a counter-clockwise manner in Figure 7 the frictional contact of the sheet material 48 on the periphery of the pattern 18 will drive applicator roller 151 to cause it to gather dye solution 156 from the trough and apply it to the projections 19 on the pattern after which these projections 19 will transfer the solution to the material 48 to print the same. In this form of the invention, it is preferable that the background of the pattern be made of non-absorbent material and the raised portions 19 be made of absorbent material so that only the raised portions will transfer dye to the fabric.

Both of the modified forms shown in Figures 5, 6, and 7 may have the means shown in the preceding form for removing the sheet to be marked from contact with the pattern roll for positioning the pattern roll.

In the drawings and specification there has been set forth a preferred embodiment of the invention, and although specific terms are employed, they are used in a generic and descriptive sense only, and not for purposes of limitation, the scope of the invention being set forth in the appended claims.

I claim:

1. Apparatus for marking a long section of cloth for indicating thereon a design for bed-spreads, bath mats and the like, comprising a framework, a pattern roll mounted for rotation on the framework, a pattern having a design thereon in relief and mounted upon the pattern roll, a marking roll mounted for rotation in the framework in the same direction as the pattern roll and wipingly contacting the section of cloth for pressing the same against the pattern on the pattern roll as the cloth and the periphery of the pattern roll pass the marking roll and means for axially reciprocating the marking roll.

2. Apparatus for marking a long section of cloth for indicating thereon a design for bed-spreads, bath mats and the like, comprising a framework, a pattern roll mounted for rotation on the framework, a pattern having a design thereon in relief and mounted upon the pattern roll, a marking roll mounted for rotation in the framework and contacting the section of cloth for pressing the same against the pattern on the pattern roll as the cloth and the periphery of the pattern roll pass the marking roll, and means for imparting rotation to the marking roll in the same direction as the pattern roll whereby the surface of the marking roll will be moving in a direction opposed to the adjacent surface of a pattern roll to provide a wiping contact with the sheet of material.

3. Apparatus for marking a long section of cloth for indicating thereon a design for bed-spreads, bath mats and the like, comprising a framework, a pattern roll mounted for rotation on the framework, a pattern having a design thereon in relief and mounted upon the pattern roll, a marking roll mounted for rotation in the framework and contacting the section of cloth for pressing the same against the pattern on the pattern roll as the cloth and the periphery of the pattern roll pass the marking roll, and means for imparting rotation to the marking roll in the same direction as the pattern roll, whereby the surface of the marking roll will be moving in a

direction opposed to the surface of the pattern roll, thereby providing a wiping contact with the sheet of material, the marking roll being composed of a mixture of oleaginous material and coloring matter.

4. Apparatus for marking a long section of cloth for indicating thereon a design for bed-spreads, bath mats and the like, comprising a framework, a pattern roll mounted for rotation in the framework, a pattern having a design thereon in relief and mounted upon the pattern roll, a marking roll mounted for rotation in the framework and contacting the section of cloth for pressing the same against the pattern on the pattern roll as the cloth and the periphery of the pattern roll pass the marking roll, means for imparting rotation to the marking roll in the same direction as the pattern roll whereby the surface of the marking roll will be moving in a direction opposed to the surface of a pattern roll, thereby providing a wiping contact with the cloth, and means for releasing the cloth from contact with the pattern roll for repositioning the pattern roll relative to the cloth.

5. Apparatus for marking a long section of cloth for indicating thereon a design for bed-spreads, bath mats and the like, comprising a framework, a pattern roll mounted for rotation on the framework, a pattern having a design thereon in relief and mounted upon the pattern roll, a marking roll mounted for rotation in the framework and contacting the section of cloth for pressing the same against the pattern on the pattern roll as the cloth and the periphery of the pattern roll pass the marking roll, means for imparting rotation to the marking roll in the same direction as the pattern roll whereby the surface of the marking roll will be moving in a direction opposed to the surface of the pattern roll, thus providing a wiping contact with the cloth, the marking roll being composed of a mixture of oleaginous material and coloring matter, and means for removing the cloth from contact with the pattern roll for repositioning the pattern roll relative to the cloth.

6. Apparatus for marking a long section of cloth for indicating thereon a design for bed-spreads, bath mats and the like, comprising a framework, a pattern roll mounted for rotation on the framework, a pattern having a design thereon in relief and mounted upon the pattern roll, a marking roll mounted for rotation in the framework and contacting the section of cloth for pressing the same against the pattern on the pattern roll as the cloth and the periphery of the pattern roll pass the marking roll, weighted means for pressing the marking roll into engagement with the cloth passing over the pattern roll, and means for axially reciprocating the marking roll while it is rotating.

7. Apparatus for marking a long section of cloth for indicating thereon a design for bed-spreads, bath mats and the like, comprising a framework, a pattern roll mounted for rotation on the framework, a pattern having a design thereon in relief and mounted upon the pattern roll, a marking roll mounted for rotation in the framework and contacting the section of cloth for pressing the same against the pattern on the pattern roll as the cloth and the periphery of the pattern roll pass the marking roll, and means for reciprocating the marking roll axially while the same is rotating.
